US00D873230S

(12) **United States Design Patent** (10) **Patent No.:** **US D873,230 S**
(45) **Date of Patent:** ** *Jan. 21, 2020

(54) **ELECTRONIC DEVICE**

(71) Applicant: **Samsung Electronics Co., Ltd.**, Suwon-si (KR)

(72) Inventors: **Jae-Hun Seo**, Suwon-si (KR); **Hyok-Su Choi**, Seoul (KR); **Hyoung-Shin Park**, Seoul (KR); **Yun-Jin Kim**, Seoul (KR)

(73) Assignee: **SAMSUNG ELECTRONICS CO., LTD.**, Suwon-si (KR)

(*) Notice: This patent is subject to a terminal disclaimer.

(**) Term: **15 Years**

(21) Appl. No.: **29/621,521**

(22) Filed: **Oct. 9, 2017**

(30) **Foreign Application Priority Data**

Apr. 14, 2017 (KR) 30-2017-0017539

(51) **LOC (12) Cl.** **14-03**

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings illustrate portions of the electronic device that form no part of the claimed design.

1 Claim, 8 Drawing Sheets
